(57) **CLAIM**

The ornamental design of the LED illumination unit, as shown and described.

DESCRIPTION

FIG. 1 is a front perspective view of a first embodiment of a LED illumination unit;

FIG. 2 is a rear perspective view of the LED illumination unit of FIG. 1;

FIG. 3 is a front view of the LED illumination unit of FIG. 1; FIG. 4 is a rear view of the LED illumination unit of FIG. 1; FIG. 5 is first side view of the LED illumination unit of FIG. 1;

FIG. 6 is a second side view of the LED illumination unit of FIG. 1;

FIG. 7 is a top view of the LED illumination unit of FIG. 1; and,

FIG. 8 is a bottom view of the LED illumination unit of FIG. 1.

The broken line portions of the drawings are for illustrative purposes only and form no part of the claimed design.
